UNITED STATES PATENT OFFICE.

DELL S. CROSBY AND JULIUS R. MEYERS, OF CHICAGO, ILLINOIS.

DESIGN FOR A CHEESE.

SPECIFICATION forming part of Design No. 33,706, dated December 11, 1900.

Application filed November 12, 1900. Serial No. 36,300. Term of patent 7 years.

To all whom it may concern:

Be it known that we, DELL S. CROSBY and JULIUS R. MEYERS, citizens of the United States, residing at Chicago, county of Cook, 5 and State of Illinois, have invented and produced a new and original Design for a Cheese, of which the following is a specification, reference being had to the accompanying drawing, forming a part hereof.

10 Said drawing illustrates in perspective a cheese made in accordance with our novel design.

15 The essential or characteristic features of a cheese made in accordance with our novel design are as follows: Said cheese has the form of a symmetrical oblong polygonal figure and is generally rectangular in plan view. The side and end faces of the cheese taper slightly from the upper to the lower faces thereof.

20 On one face of the cheese is formed a plurality or series of shallow transverse depressions which are parallel with each other and the

shorter faces or ends of the cheese. Said depressions terminate short of the side edges of the face in which they are formed on both 25 sides of the cheese, thereby leaving a border at the edges of said face surrounding said depressions. Said depressions are located at equal distances apart, and the two depressions at the ends of the series are located a distance 30 from the short or end faces of the cheese slightly greater than the distance between adjacent depressions.

We claim as our invention—

25 The design for a cheese substantially as 35 herein shown and described.

Signed at Chicago, Illinois, this 9th day of November, A. D. 1900.

DELL S. CROSBY.
JULIUS R. MEYERS.

In presence of—

C. CLARENCE POOLE,
WILLIAM L. HALL.
